G. A. KNAPP

DETACHABLE CAN SPOUT

Filed Jan. 26, 1926.

Fig. 1.

Fig. 2.

UNITED STATES PATENT OFFICE.

GEORGE A. KNAPP, OF SPOKANE, WASHINGTON.

DETACHABLE CAN SPOUT.

Application filed January 26, 1926. Serial No. 83,931.

This invention relates to improvements in detachable spouts for cans for facilitating egress of liquid contents therefrom.

The device of my invention is generally 5 L-shaped and it is a novel feature to provide the same with a tapered piercing limb whereby the can top may be readily pierced to permit partial insertion of the spout therein.

It is a feature of my invention to form the 10 remaining limb as a pouring limb, the same being provided with pouring and air vent passages of a novel formation to facilitate egress of the liquid contents.

It is also a feature of my invention to provide 15 means for effectively sealing the can after the device of my invention has been applied thereto so that evaporation will be reduced to a minimum.

In this connection, it is a feature of my 20 invention to provide means for causing one or more portions of the device to positively engage the can when secured thereto for the purpose of rigidly holding the device in position.

25 My invention has many other features and objects that will be more fully described in connection with the accompanying drawing and which will be more particularly pointed out in and by the appended claims.

30 In the drawing:—

Fig. 1, is a view in section of a can and showing how the device of my invention is inserted therein.

Fig. 2, is a similar view after the device 35 has been inserted and before the same has been secured in an inserted position.

Fig. 3, is a view showing the device secured in a fixed position.

Fig. 4, is a plan view thereof with the 40 close omitted.

Fig. 5, is a sectional view of the spout detached from its associated parts.

Like characters of reference designate 45 similar parts throughout the different figures of the drawing.

The device of my invention includes a substantially L-shaped spout having a piercing limb 1 and a pouring limb 2. The piercing limb 1 tapers from what I will term its juncture end 3, to a sharply pointed piercing end 4. As will be seen by reference to Fig. 5, the piercing limb is slightly arcuate, which form disposes the sharp end or terminal 5, at a sufficient elevation with the mid-center 50 portion 6, to insure engagement of the terminal 5, with the under face 7, of the top 8,

of the can 9, when the device is in a final tightened adjustment, as shown in Fig. 3.

The end 4, is preferably solid, but the limb is hollow as indicated at 10, from the solid portion toward the juncture end 3, to form an air vent passage. The discharge outlet for said passage is indicated at 11, and the same opens through the periphery of the prong and preferably upwardly with respect thereto in a manner to freely communicate with the interior of the can. It is also a feature of my invention to make the limb 1, relatively elongated thereby affording a sufficient leverage in order to render it more 70 effective in stabilizing the spout, as will be more fully described.

The remaining or pouring limb designated at 2, joins the piercing limb 1, at an elbow or juncture, and I preferably make the pouring limb of slightly less diameter than the larger cross section of the piercing limb so that a substantial shoulder 12, will be formed, the main function of which is to bend double the mutilated portions of the can resulting from the piercing operation. This affords a better engagement of the spout with the perforated top of the can, as will later appear, although this is not an essential feature of my invention. The pouring limb 2, 80 is tubular and preferably cylindrical and its upper open end 13, is inclined as shown to facilitate pouring of the liquid contents of the can. I have shown the pouring limb partitioned off as by a partition 14, which 85 functions to divide the limb into an inner air vent passage 15, communicating with passage 10, and an outer pouring passage 16. The pouring passage 16 has an intake at 17, disposed below the top 8, of the can and always un-obstructed to ingress of the liquid 90 contents.

It is a feature of my invention to provide the device with means whereby not only a tight closure of the can may be effected, but which means also performs the additional function of causing a portion of itself and a portion of the spout to so engage the can as to stabilize the device thereon when said device is attached thereto, 105 which means I will next describe in detail.

On the pouring limb 2, is a cam lug 17. A cam sleeve 18, is rotatively adjustable on said limb 2, and has a cam edge 19, adapted for coaction with lug 17. I dispose a yielding washer 20, about limb 2, and preferably upon this washer is a metal washer 21, the

latter being adapted not only to take the wear but also to distribute the compression of washer 20. The cam sleeve 18, has an actuator 22 which is preferably winged shaped, and which forms, as shown, a continuation of said sleeve 18. In order to render said sleeve easily attachable and detachable to and from limb 2, I terminate one edge or end 23, thereof, short of a complete circle whereby the sleeve can be slipped on and off from the end of limb 2. Said actuator 22 has a lower edge 24, adapted to engage the top of the can 9, and to its upper edge 25, is pivoted at 26, a spout closure 27, having a handle lever 28. A spring 29, serves normally to seat said closure 27.

The operation of my device is as follows:—

The limb 1 is inserted as shown in Fig. 1, 20 until it has reached an inside position in the can, whereupon, it is shifted into the position shown in Fig. 2. When the device is in the Fig. 2, position, it is not only unstable but it is loosely disposed in the can top 8. 25 Next, the actuator 22, is turned from the Fig. 2 to the Fig. 3, position, the turning movement being clockwise, viewing Fig. 4. This adjustment of the actuator 22, causes edge 19 to coact with lug 17, and elevate 30 the device to the position shown in Fig. 3, wherein the end 4 is in engagement with the top 8, and the enlarged shoulder 12, fits snugly in the opening pierced by the limb 1. The edge 24, of the actuator 22, bears downwardly on top of the can in opposition to 35 end 5, and between the end 4, and shoulder 12. Irrespective of the shoulder 12, the bight 30, and end 4, would afford spaced points of contact or engagement with the 40 top of the can in the absence of the enlarged juncture of the limbs. Thus, I not only obtain a substantially air tight closure of the can, but I also obtain a very rigid detachable connection therewith.

45 Now as the can is tilted, in the usual way, the liquid contents can egress from passage 16, and the air will ingress through 15 and 10 and discharge into the can through opening 11.

50 It is believed that the device of my invention will be fully understood from the foregoing description and while I have herein shown one form of my invention, I do not wish to be limited thereto except for such 55 limitations as the claims may import.

I claim:—

60 1. A detachable can spout of substantially L-shaped form having a pouring and a piercing limb, said piercing limb being hollow and having a sharply pointed solid end and being gradually enlarged in cross section toward its juncture with said pouring limb and said piercing limb being gently curved to dispose its pointed end in engagement 65 with the under face of the can top when said

device is in a pouring position, and said piercing limb having an air vent passage extending longitudinally thereof and provided with a discharge end opening through the periphery of said piercing limb between the 70 pointed and juncture ends thereof, and said pouring limb being tubular and having a longitudinal partition forming therein an inner vent passage communicating with the vent passage of said piercing limb and an outer pouring passage opening through the periphery of the juncture of said limbs below the can top, said pouring limb having a cam lug near its outer extremity, a yielding washer on said pouring limb adapted for external engagement with the pierced opening in the can top, and a cam sleeve rotatable on said pouring limb and coacting with said lug to compress said washer and draw the pointed end of said piercing limb against the can top, and said can sleeve having an actuating wing adapted for engagement with the can top in opposition to said piercing limb to stabilize the spout when the latter is tightened into position.

2. A detachable can spout of substantially L-shaped form having a pouring and a piercing limb, said piercing limb having an air vent passage provided with a discharge end opening to the interior of the can, and said pouring limb being tubular and longitudinally partitioned to form an inner air vent passage communicating with the vent passage of said piercing limb and an outer pouring passage opening through said limb 85 interiorly of the can, and said pouring limb having a cam lug, a yielding washer surrounding said pouring limb adapted to close the pierced opening in said can, and a cam sleeve rotatable on said pouring limb and coacting with said lug to compress and spread said washer against the can top, and said sleeve having an actuating wing adapted for engagement with the can top when in a final 90 position to stabilize the spout.

3. A detachable can spout of substantially L-shaped form having a pouring and a piercing limb, said piercing limb having an air vent passage provided with a discharge 95 end opening to the interior of the can, and said pouring limb being tubular and longitudinally partitioned to form an inner air vent passage communicating with the air vent passage of said piercing limb and an outer pouring passage opening through said limb 100 interiorly of the can, a yielding washer on said pouring limb adapted to close the pierced opening in the can, and means coacting with said pouring limb for compressing and spreading said washer and anchoring 105 said spout to said can.

4. A detachable can spout of substantially L-shaped form having a pouring and a piercing limb and said piercing limb being arcuate from its free end toward the elbow 110

juncture of said L-shaped spout, and means co-acting with said pouring limb and can top to draw the elbow end of said piercing limb against said top and said means engaging the can top between said elbow and said free end of said piercing limb to draw said free end against the bottom of the can top, thereby firmly securing said spout to the can.

5. A detachable can spout of substantially L-shaped form having a pouring and a piercing limb, the elbow portion being slightly enlarged for subjacent engagement with the bent stock at the margin of the pierced opening, a resilient washer on said pouring limb for superimposed engagement with the upper face of the opening, and means stressing the spout in an upward direction and compressing said washer in a

downward direction to firmly secure said spout to the can top.

6. A detachable can spout of substantially L-shaped form having a piercing limb tapered to a solid imperforate point, the remainder of said limb having an air vent passage opening peripherally of said limb into the can, said spout having a pouring limb provided with an air vent passage communicating with said air passage of said piercing limb, and said pouring limb having a pouring passage opening through said spout to the interior of the can, and means for securing said spout to the can.

In testimony that I claim the foregoing as my own, I hereby affix my signature.

GEORGE A. KNAPP.
